UNITED STATES PATENT OFFICE

122,327

DESIGN FOR A DOUBLE DIAL CLOCK

John M. Winans, Binghamton, N. Y., assignor to
International Business Machines Corporation,
New York, N. Y., a corporation of New York

Application June 19, 1940, Serial No. 93,099

Term of patent 14 years

To all whom it may concern:

Be it known that I, John M. Winans, a citizen
of the United States, residing in Binghamton, in
the county of Broome and State of New York,
have invented a new, original, and ornamental
Design for Double Dial Clocks, of which the fol-
lowing is a specification, reference being had to
the accompanying drawings, forming part
thereof.

Fig. 1 is a front view of a double dial clock
showing my new design, the opposite side pre-
senting substantially the same appearance.

Fig. 2 is a side view of the same; and
Fig. 3 is a top plan view thereof.

I claim:

The ornamental design for a double dial clock,
substantially as shown and described.

JOHN M. WINANS.
